UNITED STATES PATENT OFFICE.

SAMUEL TURNER AND THOMAS EASTAUGH, OF ROCHDALE, ENGLAND, ASSIGNEES TO
SAMUEL TURNER & COMPANY, LIMITED, OF SPOTLAND, ROCHDALE, ENGLAND.

LOOM FOR WEAVING.

Application filed September 26, 1928, Serial No. 308,396, and in Great Britain July 2, 1927.

This invention relates to looms for weaving and has for its object to provide improved arrangements for adjustment for different widths of cloth to be woven.

5 The invention consists in a loom for weaving in which the cloth temples are adjustably mounted on a bar.

The invention also consists in other details hereinafter indicated.

10 The accompanying drawings illustrate one mode of carrying out the invention:—

Figure 1 is a more or less diagrammatic plan showing the breast beam and sley of an automatic weft replenishing loom with parts 15 mounted and arranged thereon in accordance with the invention;

Figure 2 is a plan of the temples shown in Figure 1, the cover being removed from one, and

20 Figure 3 is a section on the line 3—3 of Figure 2.

In carrying our invention into effect we may apply our improvements to existing looms or to looms specially built for the 25 purpose, and such looms may, if desired, be provided with the usual accessories incidental to weft replenishing looms.

The cloth temples *a* for maintaining the cloth stretched are adjustably mounted upon a bar or other support *b* so that they may be 30 readily adjusted for different widths of cloth to be woven, and we prefer that the rollers *c* of the temple (which may or may not be conical) shall be set at an angle to one another (as shown in Figure 2), while the tongue *d* of the temple cover which passes down between the rollers is also somewhat inclined and in this way a better tension will be maintained upon the cloth.

40 The depth of the tongue increases at the end of the temple where the distance between the axes of the rollers *c* is greatest. The cloth, as usual, is passed over the roller at

one side of each temple, under the tongue *d* and over the roller at the opposite side of the 45 temple.

The tongue *d*, when the temples are used in connection with medium and heavy cloths, acts to hold the selvedges tightly owing to the tongue pressing deeper between 50 the two inclined rollers *c* than has previously been the case with the result that the weaving is better and better selvedges are obtained.

The arrangement also enables us to provide an improved form of temple weft cutter which consists of a circular blade or knife *e* or other like ring cutter fitted on to one of the roller pins at the outside end of the roller, such improved construction of 55 temple and temple cutter enabling the temples to be fixed very near to the fell of the cloth, which ensures good weaving.

It will be understood that the invention is not to be limited to the foregoing details 60 of construction which are given by way of example only, nor is it to be limited to any particular type or construction of weft replenishing or other loom to which it is to be applied.

Having now described our invention, what we claim as new and desire to secure by Letters Patent is:—

In a loom for weaving, a temple including a pair of spaced rollers, the axes of said 75 rollers being inclined to each other, a cover for said rollers, and a longitudinal tongue on said cover disposed between said rollers and increasing in depth in the direction of increase in the distance between the inclined 80 rollers.

In testimony whereof we have signed our names to this specification.

SAMUEL TURNER.
THOMAS EASTAUGH.
